HARP SWIVEL

Paul Chilo, Chicago, Ill.

Application June 17, 1950, Serial No. 168,810

4 Claims. (Cl. 240—148)

1

This invention relates to lamp shade holders for electric lamps, and more particularly to harp swivels for adjustably mounting a lamp shade upon a lamp harp, and is an improved form of lamp shade holder over that disclosed and claimed in my United States Patent No. 2,495,209 granted January 24, 1950.

It is a principal object of the invention to provide a simple harp swivel construction in which the lamp shade may be adjusted at an angle about an axis of a transverse member of a lamp harp, and similarly adjusted angularly about an axis at right angles to the first-mentioned axis as the harp swivel may be adjusted or rotated in either direction about said axis of the transverse member.

Another object of the invention is to provide a harp swivel including the mounting for the lamp shade which is clamped together for frictionally holding the lamp swivel in its various adjusted positions about the axes at right angles to one another.

Another object of the invention is to provide a lamp swivel construction which is simple and economical to manufacture.

In accomplishing the various objects of the invention, I have provided a simple form of harp swivel comprising a support member which swivels upon the lamp harp for adjusting the lamp shade in one direction, and a support to which the lamp shade is attached providing an adjustment at right angles to the first-mentioned adjustment, wherein the harp swivel may be adjusted with respect to the harp of the lamp with an indeterminate number of adjustments in either plane as the lamp shade is swung upon the lamp harp.

I have also provided another embodiment of a harp swivel similar to the first embodiment by employing a slotted, cup-shaped member adapted to rotate about the axis of a transverse member of a lamp harp, and limiting the angular adjustment in either direction about an axis perpendicular to the first axis as the harp swivel is swiveled upon the lamp harp.

Many other objects and advantages of the construction herein shown and described will be obvious to those skilled in the art from the disclosure herein given.

To this end my invention consists in the novel construction, arrangement, and combination of parts herein shown and described, and more particularly pointed out in the claims.

Referring now to the accompanying drawing forming part of the specification;

2

Fig. 1 is a vertical view of a lamp harp provided with the improved harp swivel;

Fig. 2 is an enlarged view, partly in section, illustrating the harp swivel and decorative knob 5 for adjusting the lamp shade;

Fig. 3 is a vertical, sectional view taken along line 3—3 of Fig. 2 illustrating the frictional connection for the pivot connections of the harp swivel;

10 Fig. 4 is an enlarged view similar to Fig. 2 illustrating a modified form of harp swivel connection;

Fig. 5 is a vertical, sectional view taken along line 5—5 of Fig. 4 illustrating the pivot connections of the modified harp swivel; and

Fig. 6 is an enlarged, perspective view of the cup-shaped member for limiting the adjusting movement of the harp swivel of the embodiment of Fig. 4.

20 Referring now more particularly to the drawing, an improved harp swivel connection 10 is mounted on a lamp harp 11 for supporting a lamp shade frame 12 in a well-known manner.

The conventional lamp harp 11 has a bottom connection 13 for mounting on the lamp base, and a transverse support 14 upon which the swivel connection is adjustably mounted. The harp swivel 10 preferably comprises a support member 15 substantially U-shaped swingably mounted upon the transverse support 14.

30 A lamp shade mounting 16 is pivotally mounted upon the support member 15 at the point of connection thereto, so that it swings about its axis perpendicular to the axis of the transverse member 14.

35 Suitable means for fastening the lamp shade mounting to the support member 15 is preferably formed as a rivet or rivet connection 17. In assembling the support member 15 and the lamp shade mounting 16 by riveting, the rivet 17 is so

40 assembled that the harp swivel assembly 10 is retained in its adjusted position either about the transverse support 14, or in its adjusted position about the axis transverse to that of the support member provided by the riveted connection between the support member 15 and the lamp shade mounting 16.

45 The lamp shade mounting 16 is formed with a downward extending projection 18 to which the support member 15 is riveted. A disk-shaped support 19 integrally formed with the projection 18 provides a support for the lamp shade frame 12, and the lamp shade frame is affixed to the harp swivel by a threaded, ornamental knob 20 in threaded engagement with an upwardly extending, threaded stud 21. It is preferred to form

the lamp shade mounting 16 as a molded or die cast member, although it is within the scope of the invention that it may be suitably fabricated of from rods of the diameter of the disk-shaped portion 19, preferably as a screw machine operation and a milling machine operation.

It is preferred to secure the support member 15 and lamp shade mounting 16 by riveting in order that the two members are so assembled that, in whatever adjusted position of the support member 15 about its transverse axis and the angular adjustment of the lamp shade 16 about its axis provided by the rivet connection 17, the members 15 and 16 will be frictionally affixed together to be held in their respective adjusted positions. It is to be understood, however, that it is within the scope of the invention that the members may be affixed together with any other suitable form of connection, such as screw and nut. Referring to Fig. 3, in order to provide this frictional joint, the member 15 is U-shaped, and when riveted or affixed together to the lamp shade mounting 16, the legs of the U-shaped member 15 are frictionally clamped to the projection 18, and to the transverse support 14, as shown.

With this improved form of harp swivel, it is possible to adjust the lamp shade 12 in any position about the axis of the transverse support 14. It is also possible to swing the lamp shade about the axis of the rivet connection 17 between the members 15 and 16 in either direction in any adjusted position of the support member 15 about its transverse axis. It is thus obvious that a simple form of universal connection has been provided for a harp swivel for adjusting the lamp shade mounted thereon in any desired position.

Referring to Figs. 4 and 6, I have also provided another embodiment of my invention in a harp swivel connection similar to that illustrated and described above in connection with Figs. 1, 2, and 3, but which provides a shield for the swivel connection, and also limits the angular adjustment of the harp swivel about the pivotal axis between the support member 15 and lamp shade mounting 16. Like reference characters will denote the smaller similar parts, and only those parts will be particularly described which have been slightly modified from that of the first embodiment.

The modified swivel connection or harp swivel 22 comprises the U-shaped support member 15' somewhat smaller than that of the previously described U-shaped member 15 affixed to a modified lamp shade mounting 16'. The members 15' and 16' are riveted together in the same manner by the rivet connection 17 to provide for frictional engagement of the U-shaped member 15' with a downwardly extending projection 18'. A disk-shaped support 23, similar to the disk-shaped member 19 but smaller in diameter, is provided since it is only necessary to support a cup-shaped member 24 which, in this embodiment, serves as a support for the lamp shade frame 12. The lamp shade frame is affixed to the harp swivel connection 22 by an ornamental knob 20 in threaded engagement with the threaded stud 21.

The cup-shaped member 24, which provides a support for the lamp shade frame 12 by the surface 25, is formed with an opening 26 through which is positioned the threaded stud 21 for mounting the cup-shaped member upon the harp swivel 22, the member 24 and stud 21 being secured together by suitable means, as for example,

a press fit. The downwardly extending peripheral surface 27, which forms a shield for the harp swivel, is provided with diametrically positioned slots 28 in which is positioned the transverse member 14 of the lamp harp 11.

Upon adjustment of the harp swivel about its axis formed by the riveted connection 17 in any position of the support member 15', the slots 28 permit this angular adjustment, and the maximum adjustment about the rivet connection 17 in either direction is limited by the depth of the slots 28.

As previously described above with respect to the embodiment of Figs. 1, 2, and 3, the support member 15', the projection 18', and the transverse support 14 are frictionally held together to maintain the harp swivel 22 in any of its adjusted positions, either about the axis of the rivet connection 17, or about the axis of the transverse member 14. The member 15' frictionally engages the peripheral surface of the transverse member 14 as it is angularly adjusted.

In assembling the harp swivel connections 10 and 22 of each embodiment to a conventional form of lamp harp 11, the members 15 and 15' are fabricated into the U-shaped constructions shown in Figs. 3 and 5. The members 15 and 15' are then assembled upon their respective transverse support 14, after which the lamp shade mountings 16 and 16' are assembled to their respective support members 15 and 15' by riveting, and the rivet connection 17 provided is such that a frictional adjustment is provided between the members 15, 15' and their respective projections 18, 18' to which they are attached. Similarly, the members 15 and 15' are frictionally attached to their respective transverse support 14 so that in any adjusted position of the harp swivel, the various members thereof are frictionally held in their adjusted position. The ornamental knob 20 may then be threaded upon the respective studs for the embodiment of Fig. 1, and in the embodiment of Figs. 4, 5, and 6, the cup-shaped member 24 is mounted upon its stud 21, after which the knob 20 may be mounted as shown in Fig. 4. In either of the constructions, the lamp shade is attached or detached by removing the ornamental knob 20 and placing the lamp shade frame 12 in position upon the respective harp swivels 10 or 22, as illustrated in Figs. 2 and 4, after which the ornamental knob is reassembled.

It is thus evident that there has been disclosed two embodiments of a simple form of harp swivel connection which permits of universal adjustment of the lamp shade upon the lamp harp, which is furnished with the harp swivel of this invention. Irrespective of the adjusted position of the harp swivel in any direction, the lamp shade is frictionally held in its adjusted position, but it may be moved into any other adjusted position with a simple movement through the ornamental knob 20.

It is also obvious that there has been described two embodiments of a preferred form of harp swivel which are simple and economical to manufacture. Although the various parts of the embodiments of the harp swivels have been described as being fabricated from sheet metal and rods, it is to be understood that it is within the scope of the invention that they may be cast or molded from suitable material.

Having thus described my invention, it is obvious that various immaterial modifications may be made in the same without departing from the

spirit of my invention; hence, I do not wish to be understood as limiting myself to the exact form, construction, arrangement, and combination of parts herein shown and described or uses mentioned.

What I claim as new and desire to secure by Letters Patent is:

1. The combination with a lamp harp having a transverse support in the plane of the lamp harp for mounting a lamp shade, of a harp swivel comprising U-shaped means complementally formed to the transverse support for frictional engagement therewith and adjustably mounted upon the transverse support, stud means for detachably mounting a lamp shade, including a downwardly extending projection engaging the sides of the U-shaped means, adjustable angularly about a pivot connection to the U-shaped means, cup-shaped means for limiting the angular movement of the stud means for detachably mounting a lamp shade in either direction in a plane perpendicular to the axis of the pivot connection, and said cup-shaped means for limiting the angular movement provided with opposed slots complementally formed to the transverse support, whereby the stud means for detachably mounting a lamp shade is adapted to swing in either direction about the axis of the transverse support in any of the adjusted positions of the aforesaid means for detachably mounting a lamp shade about its pivot connection.

2. The combination with a lamp harp having a transverse support in the plane of the lamp harp for mounting a lamp shade, of a harp swivel comprising U-shaped means complementally formed to the transverse support to frictionally engage it and adjustably mounted upon the transverse support, stud means for detachably mounting a lamp shade, including a downwardly extending projection, and being adjustable angularly about a pivot connection to the U-shaped means, and cup-shaped means formed with oppositely spaced slots complementally formed to the transverse support and adapted to engage the transverse support permitting swinging of the harp swivel about the axis of the transverse support in either direction.

3. The combination with a lamp harp having a transverse support for mounting a lamp shade, of a harp swivel comprising a U-shaped support member swingably mounted upon the transverse support and complementally formed thereto to

frictionally engage the transverse support, a lamp shade mounting provided with a stud and comprising downwardly extending means complementally formed to the U-shaped support, 5 said lamp shade mounting swingably mounted upon the support member at an axis transverse to the support member, and rivet means extending through the support member and the downwardly extending means of the lamp shade mounting for frictionally affixing the lamp shade mounting to the support member and the U-shaped support member to the transverse member, whereby the harp swivel is frictionally retained in its adjusted position either about the transverse support or in its adjusted position about the axis transverse to the support member.

4. The combination with a lamp harp having a rod-like transverse support for mounting a lamp shade, of a harp swivel comprising complementally formed members, one member of which 10 forming a support member is swingably mounted upon the rod-like transverse support, and the other member is swingably mounted upon the first-mentioned member at an axis transverse to the transverse support, 15 said last-mentioned member including a lamp shade mounting, a single securing means extending through the complementally formed members to form a pivotal connection for the complementally formed members at the aforesaid transverse axis, and said single securing means also frictionally affixing the members together at the pivotal connection and the support member to the transverse support, whereby the harp swivel is frictionally 20 retained in its adjusted position either about the transverse support or in its adjusted position about the axis transverse to the support member.

PAUL CHILO.
